UNITED STATES PATENT OFFICE.

PERCY W. MARTIN, OF BAY CITY, MICHIGAN, ASSIGNOR TO SMALLEY GENERAL COMPANY, OF BAY CITY, MICHIGAN, A CORPORATION OF MICHIGAN.

CLAMPING TUBE FOR THREAD MILLERS AND THE LIKE.

1,412,809.

Specification of Letters Patent. Patented Apr. 11, 1922.

Original application filed May 24, 1918, Serial No. 236,334. Divided and this application filed June 22, 1920. Serial No. 390,845.

To all whom it may concern:

Be it known that I, PERCY W. MARTIN, citizen of the United States, residing at Bay City, in the county of Bay and State 5 of Michigan, have invented certain new and useful Improvements in Clamping Tubes for Thread Millers and the like; and I do hereby declare the following to be a full, clear, and exact description of the invention, such as 10 will enable others skilled in the art to which it appertains to make and use the same.

This invention relates to improvements in thread milling machines, lathes and the like and pertains more particularly to improved 15 means whereby the cutting hob may be quickly and accurately located in operative position relative to the work to be threaded.

The construction and arrangement of parts in my improved device has for its 20 further object to provide a simple and effective means whereby the cutting hob may be started into the cut or thread which is to be formed in the work in such manner that the hob will enter the work at exactly 25 the place desired. In other words, there shall be no play or back-lash in the hob or its feed mechanism.

The absence of back-lash in a thread-milling machine of the character to which my 30 invention is applicable is of the utmost importance in practice, because there are many classes of work in which it is imperative that the commencement of the thread in the finished work shall be exactly in the 35 same position on successive pieces of work. For example, in the cutting of threads on the jaws or "chasers" commonly used in dies for cutting pipe threads and the like, it is essential not only that the threads be 40 cut accurately on the successive chasers comprising a "set", but, in order that corresponding chasers taken from different sets of chasers may be interchangeable, it is also absolutely necessary that the threads on the 45 corresponding chasers commence at exactly the same point.

Otherwise, if, say, the number 2 chaser of one set were taken out and the number 2 chaser of another set were substituted for it, 50 and if the threads on the two number 2 chasers did not commence at exactly the same point on both, the completed "set" of chasers when assembled in a die stock would not cut a proper thread, the reason being

that the number 2 chaser of the second set 55 would not track with number 1 and number 3 chasers of the first set, and the number 2 chaser of the second set would, therefore, "pare" the thread in the finished work. In other words, the corresponding chasers of 60 successively manufactured sets are ordinarily not interchangeable and consequently it has heretofore been necessary when one chaser of a set became damaged to discard the entire set, the cause of such imperfection being that the successively manufactured chasers did not have their threads commence at exactly the same point, and this variation was generally caused by the presence of backlash in the cutting mechanism of the milling machine or lathe in 70 which the chasers were threaded.

There are many other examples of classes of work in which it is essential that the threads be accurately started and that 75 threads in successive pieces of work be commenced at exactly the same location on the successive pieces. It is also necessary to avoid back-lash in the rapid production of perfect threads in other classes of commercial work, such as pipe threads, bolts, etc., aside from the manufacture of chasers.

It is not possible in a thread-miller which has back-lash in its feed mechanism to rapidly produce duplicate work that meets the 85 above rigid requirements, because the lead is usually thrown into action in such machines by clamping the lead-screw by means of a threaded split nut or its equivalent. When such a split nut is thrown into engagement with the lead-screw it frequently happens that the threads of the nut do not come fair with the threads on the lead-screw and consequently gripping action between the nut and lead-screw is not instantaneously 90 accomplished and the clamping action is 95 accompanied by a slight relative movement of the lead screw and nut when the two threads come together.

With my improved device I am enabled to 100 instantly grip the stationary and moving members, so that feed starts instantly. The gripping action can take place at any point whatsoever in relation to the lead screw, without having to wait until after the above-mentioned relative longitudinal movement of the lead screw and nut has taken place. Even though the back-lash may be only a 105

few thousandths of an inch, such movements are detrimental and it is, therefore, the prime object of my present invention to provide a releasable connection between the lead screw and the hob-carriage that will effectively obviate all back-lash.

The claims of this case are directed to specific embodiments of my device and the equivalents thereof.

10 Broader aspects of the invention are presented in my copending application, Serial No. 236,334, filed May 24, 1918, to which reference may be had, this being a continuation of said application.

15 In that application, one form of connection between the lead-screw and the hob-carriage is shown.

20 In the present application I am presenting a modified form embodying certain improvements in construction while providing for the effective elimination of back-lash.

25 With the foregoing and certain other objects in view, which will appear later in the specification, my invention comprises the devices described and claimed and the equivalents thereof.

30 In the drawings, Fig. 1 is a top plan view of a thread-miller embodying my improvement.

35 Fig. 2 is a longitudinal sectional elevation of the same.

Fig. 3 is a detached view partly in section, showing the lead-screw with its traveling nut and clamp.

40 Fig. 4 is an end view of the clamp.

Fig. 5 is a perspective detail of the cage forming a part of a preferred form of frictional bearing for the traveling tube.

45 Fig. 6 is a diagrammatic view of a thread-miller chuck with chaser blanks in position to be cut, and showing the starting position of the hob circumferentially with respect to the chuck.

Fig. 7 is a fragmentary part sectional view through a chuck, showing diagrammatically the relative longitudinal starting positions of the hob and the work.

50 As is clearly shown in the drawings, and as described in my co-pending application above referred to, the machine in general consists in a base 1 carrying a main spindle 2, which is actuated by the main driving gear 3, the spindle being revolvably mounted in suitable bearings 4 and 5.

55 A cutting-hob 6 carried by a hub spindle 7 and actuated by a drive pulley 8 is mounted in the usual transverse carriage 9, this carriage being in turn mounted upon a longitudinally movable carriage 10 adapted to be moved back-and-forth by the usual traversing wheel 11, which is adapted to actuate the carriage along its guides 12, 12 and 13, 13 by means of a suitably connected rack and pinion, not shown.

65 Rotatably mounted in bearings 14 carried

by the base 1 is the lead screw 15, adapted to be rotated by a train of drive gears 16, actuated from the main spindle 2.

A nut 17 is threaded on the lead screw 15 and is secured to a traveling tube 18, which encloses the lead screw. The outer surface of the traveling tube is adapted to be releasably gripped by a clamp 19 carried by the longitudinally movable carriage 10. This clamp is preferably in the form of a slotted band, one of the ends of the band being threaded as at 20, Fig. 4, and adapted to be clamped by means of a threaded screw 21, one end of which is swiveled, as at 22, in the clamp 19.

80 Referring now to Figs. 3 and 4, it is seen that when the clamp 19 is tightened so as to grip the traveling tube 18 and hold it against turning, the continued rotation of lead-screw 15 will impart "lead" to the longitudinally movable carriage 10 and to the cutting hob 6, and that when the clamp 19 is released by means of the screw 21, the tube 18 will revolve with the screw 15 and should theoretically have no relative motion, either of rotation or axially, with respect to the screw 15; but in practice it has been found that some such relative motion is almost certain to take place while the clamp 19 is released, due to slack or clearance between the working surfaces, or through jar, accident or otherwise.

85 When clamp 19 is again engaged to start the movement of "lead" a small amount, sometimes as much as three- or four-thousandths of an inch, of back-lash or lost motion is apt to be found between the lead screw thread and the nut 17 if means is not provided to prevent this.

90 My present invention provides means for automatically preventing the occurrence of back-lash, that is to say, for automatically preventing any relative movement taking place between the lead screw 15 and the nut 17 when the clamp 19 is released from 110 and subsequently gripped to the tube 18.

95 It is apparent that if the contact between the screw 15 and nut 17 were capable of being maintained so that just the proper amount of frictional contact would always 115 occur between them, no further means would need to be provided to prevent their relative movement when clamp 19 is released or tightened; but since it is not possible in practice to maintain such thread-contact 120 permanently, I provide means for effecting frictional engagement between the tube 18 and the shank of the lead screw 15, as shown in Fig. 3, in which 23 are loose blocks of metal, wood, fibre, or other suitable material 125 arranged peripherally around the shaft of lead screw 15 and adapted to be yieldingly pressed against the shaft by springs 24 or their equivalents.

130 The blocks 23 are preferably held in place

by being inserted in longitudinal slots 25 of a sleeve or bushing 26, Fig. 5, which is received in the bore of tube 18. The end of the tube is preferably closed by a bushing 27.

The blocks 23, being yieldingly pressed against the surface of the spindle of lead screw 15 exert sufficient friction to insure that tube 18 will revolve with screw 15 as soon as 10 clamp 19 is released, without altering in the slightest the relative positions of the screw 15 and its nut 17. Thus, when clamp 19 is again tightened, no relative motion or back-lash can occur between screw 15 and nut 17, 15 and carriage 10 and its hob 6 will commence to move immediately the clamp 19 is tightened.

The absence of back-lash is due to the fact that the frictional engagement between the 20 blocks 23 and the spindle of the screw keeps the two working surfaces of the threads of the screw 15 and nut 17 always in working contact.

In the production by the thread-milling process, of successive sets of chasers which 25 shall be so accurately produced that any chaser of one set can be used interchangeably with the corresponding chaser of any other set, it is of course necessary that the 30 cutting hob shall not only have the proper axial or lengthwise motion of lead with respect to the rotation of the work, but also that in the cutting of each successive set of chasers the hob will always commence its 35 cut at exactly the same point on each chaser.

This condition is illustrated diagrammatically in Figs. 6 and 7.

Referring to Fig. 6, *a*, *b*, *c*, and *d* represent four chasers of a set to be cut by means 40 of the multiple tooth revolving hob 6. The hob is first run radially to its cutting position by proper adjustment of the carriage 9—see Fig. 2—, the clamp 19 is gripped to the traveling tube 18, and the main spindle 45 2 is started. This simultaneously starts the lead screw 15 and imparts to the hob 6 its longitudinal or lead movement in the direction of the arrow in Fig. 7.

It is obvious that one set of chasers *a*, *b*, *c*, 50 *d*, can be properly cut with one or more revolutions of the work, but after this set is finished and a new set of blank chasers is inserted in the chuck, it will not be possible to thread the individual chasers of the second 55 set so that they will operate interchangeably with the corresponding individual chasers of the first set, unless prior to the commencement of cutting the second set, the hob 6 is initially located in exactly the 60 same position radially with respect to the work, as indicated at A in Fig. 6, and unless the hob is also located in exactly the same position longitudinally with respect to the work, as in Fig. 7 on both the first and 65 second settings of the machine.

To effect the proper initial placing of the hob circumferentially, as at A, a mark or index is preferably placed upon the chuck, and after the work is clamped in the chuck, the chuck is turned until the position of 70 the mark A coincides radially with the position of the hob 6, as shown in Fig. 6. Then, before the machine is started, the hob 6 is properly located longitudinally with respect to the work. The clamp 19 is then 75 tightened to grip the tube 18.

Any desired means of locating the longitudinal starting position of hob 6 may be employed, but I prefer to use the means shown in Fig. 7, where 28 is the chuck in 80 which the chasers *a*, *b*, *c*, *d*, are mounted, and 29 is a hardened steel stop-pin fixed to the chuck 28.

By placing a suitable piece of metal called a "feeler" between the face of pin 29 and the 85 end of hob 6, a fixed distance 30 is established. Distance 30 being established, and radial position of the hob and work as indicated at A in Fig. 6, being also established, as by the means hereinbefore 90 described, and back-lash or play between the threads of lead screw 15 and nut 17 having been eliminated, is then perfectly certain that each chaser of the set *a*, *b*, *c*, *d*, will be a duplicate of and interchangeable with the 95 corresponding chaser of any other subsequently formed set of chasers.

It will be noted that whenever the tube 18 is rotated with the lead screw there is no relative longitudinal movement between the 100 tube and the lead screw, but whenever the tube is clamped and the lead screw is revolved, then there is a longitudinal movement between the tube and the screw and when the tube has reached the end of the 105 screw it is necessary to return it to its original position by rotating the screw by hand, while preventing the tube from rotating.

In practical use of this class of machines 110 it is sometimes desirable to rotate the main spindle 2 without using the lead screw, and in that case it is advantageous to not run the tube along the lead screw thread, which would make it necessary to oftener return 115 the tube by hand as above noted. Consequently my improved construction provides that when the tube is not clamped it will revolve with the lead screw, and since under these circumstances there is no relative motion between the lead screw and the tube, the tube will maintain its longitudinal position on the screw until it is again caused to operate in conjunction with the lead screw 120 by tightening clamp 19.

While I have chosen the cutting of a chaser as an illustration of the necessity of avoiding back-lash and of the necessity in certain classes of duplicating work of always starting the cut by first establishing the same cir- 130

cumferential and longitudinal positions of the hob and the work, yet it will be readily understood, as above noted, that the same requirements prevail in duplicating many other classes of thread-milling work, to all of which my present invention is well adapted.

Having thus described my invention, what I claim and desire to secure by Letters Patent is:

1. In a thread-milling machine the combination of a lead screw, a nut threaded to said lead screw, a traveling tube enclosing the lead screw and fixed to said nut, a clamp fixed to the tool carriage of the machine and adapted to releasably grip said tube, and means adapted to frictionally engage said tube and lead screw, to prevent relative movement therebetween when said clamp is disengaged.
2. In a thread-milling machine the combination of a lead screw, a nut threaded to said lead screw, a traveling tube enclosing the lead screw and fixed, at one end, to

said nut, a clamp fixed to the tool carriage 25 of said machine and adapted to releasably grip said tube, and friction members yieldingly held between said tube and lead screw and adapted to frictionally engage said tube and screw to prevent relative movement 30 therebetween when said clamp is disengaged.

3. In a thread-milling machine having a revolvable work-holding chuck and a cutting hob, the combination of a lead screw, a nut 35 threaded to said lead screw, a traveling tube enclosing the lead screw and fixed to the nut, a clamp fixed to the tool carriage of the machine and adapted to releasably grip said tube, means adapted to frictionally engage said tube and lead screw, together with a stop 40 carried by said work-holding chuck and adapted to engage the end of said hob, whereby to gauge the commencement of the cut when said clamp is caused to grip said tube, for the purposes set forth.

In testimony whereof I affix my signature.

PERCY W. MARTIN.
